UNITED STATES PATENT OFFICE.

MICHAEL C. ARMOUR, OF CHICAGO, ILLINOIS, ASSIGNOR OF ONE-HALF TO THE ADAMS & WESTLAKE MANUFACTURING COMPANY, OF SAME PLACE.

EXTENSION-TOP FOR OIL AND GAS STOVES.

SPECIFICATION forming part of Letters Patent No. 249,287, dated November 8, 1881.

Application filed March 7, 1881. (No model.)

To all whom it may concern:

Be it known that I, MICHAEL C. ARMOUR, a citizen of the United States, residing in the city of Chicago, in the county of Cook, in the State of Illinois, have invented certain new and useful Improvements in Extension-Tops for Oil and Gas Stoves, which are fully set forth in the following specification, reference being had to the accompanying drawings, in which—

10 Figure 1 is a top-plan view of an extension-top having my improvements, the center piece and covers being removed. Fig. 2 is a section of the same on the line xx in Fig. 1. Fig. 3 is a plan view of the cover, which constitutes a 15 part of my improvements.

The same letters denote the same parts in all the figures.

My invention relates to the extension-tops which are attached to oil and gas stoves to support the cooking utensils and conduct heat to them. It has been found impracticable to support the vessels on these tops in the same way as on wood or coal stoves, by setting them in holes whose edges support the vessel, inasmuch 25 as closing the top so tightly as is thus done stops up the only convenient outlet for the products of combustion, and thus smothers the flame.

The object of my invention is to obviate this 30 difficulty; and it consists in arranging within the cavity of the top supporting-ridges extending above the margins of the vessel-openings, so that when the vessels are placed on these supports there will be room for a circulation of 35 gases under them and over the edges of the openings.

It further consists in the special devices embodying this principle, which will be fully described hereinafter, and definitely pointed out 40 in the claims.

In the drawings, A denotes the central opening in the extension-top, through which the flame and gases rise from the burner. It is here represented as circular in form.

45 B denotes the flat upper surface or rim, which at each end narrows so as to be merely an incomplete ring bordering the cavity C, over which the vessels are to be set. Where it bor-

ders on the central opening it is cut away to form the steps b, which support the center 50 piece, which covers the space between the openings for the vessels when the stove is in use. The bottom of each cavity C curves upward from the edge of the central opening, A, to a level a little below that of the upper surface, B. On this bottom are formed ridges D, extending in length from the margin of the central opening nearly or quite across the cavity C. They are arranged parallel and near enough to each other to give a firm support to any vessel that may be set on them. A re-entrant curvature in the upper edge of each gives room for additional circulation of the heated currents under the vessel. By making the lower part of the vessel of less diameter than the vessel-opening the necessity of extending the ridges above the margin of the opening would be removed. When the ridges are so extended, I use for closing either of the holes the cover E, (shown in Fig. 3 of the drawings,) provided with 60 slots e, corresponding to the ridges, so that it may be set down close on the rim B, the ridges passing through it and combining with it to 65 close the opening. By closing one of the holes in this way the heat will be deflected to the 70 other. Closing both at the same time would 75 smother the flame.

What I claim as my invention, and desire to secure by Letters Patent, is—

1. An extension-top for oil or gas stoves, provided with ridges arranged within the vessel-opening and extending above its margin, substantially as and for the purpose described.

2. An extension-top for oil or gas stoves, provided with ridges D, arranged within the vessel-opening, extending above its margin, and re-entrantly curved on their upper edges, substantially as and for the purpose described.

3. In combination with the ridges D, the slotted cover E, both constructed, arranged, and operating substantially as and for the purpose described.

MICHAEL C. ARMOUR.
